OIL BURNER HEAT CONTROL APPARATUS

Guy C. Carpenter, Medford, Mass.

Application April 9, 1937, Serial No. 135,925

7 Claims. (Cl. 126—44)

My present invention relates to heat control apparatus for oil ranges, and more particularly to improvements incorporated in combination with certain apparatus disclosed in my earlier application entitled Heat control for oil burners, filed September 26, 1936, Serial Number 102,665.

The principal object of my improved apparatus is the combination of a rotatable damper operated from the outside of the range in which the oil burner is used and which makes it possible to direct the heat either over the oven or against the top of the range either in a vertical direction or at an angle thereby concentrating heat at desired points;

Another object is an improved means of mounting the apparatus and adjusting the same for various positions;

Still another object is quick demountable means for removing the apparatus with particular reference to the damper portion, and other objects comprising the construction and operation of my invention will appear as the description of the device progresses.

In the drawing illustrating the preferred embodiment of my invention,

Fig. 1 is a side elevation of the apparatus which is mounted in combination with a conventional oil range burner in a range, the range proper being shown in dot-and-dash lines;

Fig. 2 is a top plan view of apparatus particularly showing the damper control portion;

Fig. 3 is a bottom plan of the top showing the method of attaching the supporting bracket to the head portion;

Fig. 4 is a cross-section taken on the line 4—4 of Fig. 2;

Fig. 5 is a perspective view of the supporting bracket which holds the apparatus in place;

Fig. 6 is a perspective view of members which are attached to the front of the range and to which the bracket attaches;

Fig. 7 is a perspective view of the outside control member which operates the rotatable damper in the top of the apparatus, and

Fig. 8 is a side elevation, partially broken away, showing the two sleeves formed as one piece.

My present improved apparatus is designed to meet several conditions as will be explained. As shown in Fig. 1, the range 10, shown in dot-and-dash lines, may be a combination gas and oil installation in which separate independently manufactured oil burners are installed and which do not come equipped with my apparatus. In another instance the range 10 may be manufactured together with an oil burner in which is incorpo-

rated my device or, an independently manufactured oil burner using my improved apparatus may be installed in the older conventional coal or combination ranges. In each instance the installation may differ slightly incorporating some or all of the features shown in the drawing, as will be described further along in the present specification.

In the assembled view shown at Fig. 1, it is to be assumed that the apparatus is to be added to conventional oil range burners in combination with combination oil and gas ranges in which 11 illustrates a conventional perforated sleeve together with the base 12 and support 13. With such an installation, I mount my improved apparatus 14 over the sleeve 11 as a separate unit and support it in an adjustable manner on the inside surface of the range 10, as shown in Fig. 1. The apparatus proper comprises a top member 15, better shown in Figs. 1 to 4 inclusive, which is further provided with an opening 16 and a depending flange 17, the front side of which is open, as shown at 18 in the bottom plan view illustrated at Fig. 3. On the top of the top member 15 I have located boss members 19 and 20 which form open bearings in which is journaled a damper disc member 21 on trunnions 22 and 23. On the outer end of the trunnion 22 I have provided a square end 24 over which is fitted a hollow square tube 25. At Fig. 7 I have shown a regulator member comprising a shaft 26 squared at 27 and shouldered at 28 and having an indicating handle member 29, preferably positioned so that its major axis lies in the same plane as the diagonal corners of the squared end 27. In Fig. 4, it will be noted that the squared end of the trunnion 22 is located so that its diagonal corners are at right-angles to the flat sides of the damper 21 such that the indicating handle member 29, when properly assembled, will properly indicate the position of the damper from the outside of the range, as shown in Fig. 1. Preferably the unit shown at Fig. 7 is cast in one piece but it may be assembled from several pieces if desired. When the member shown at Fig. 7 is assembled, it is passed through the front of the range 10, as shown at Figs. 1 and 2, and a compression spring 26 is placed on the inside. A retaining washer 27 is then placed on the inner squared end 25 against the spring 26 and is held in place by means of a cotter-pin 28 which passes through the pin hole 29 in the member 27. The squared member 25 may be pinned at 30 to the trunnion member 24 through the pinhole 31 or, it may be fixed to the member 27, as the case may be.

It will thus be apparent that when the unit shown at Fig. 7 is pulled out from the outside of the range 10 it will be disengaged from the trunnion 22 and the damper member 21 may then be readily lifted up and off of the top 15. An eye member 32 is attached to the damper member 21 to facilitate its removal.

Attached to the under side of the top member 15 is a semi-circular sleeve member 33, the side facing the oven 34 of the range 10 being open. The sleeve 33 is held in place in any suitable manner, as by the pin 35 located in the bottom side of the top 15. This pin is located slightly to the rear so that the sleeve 33 when in place is tightly bound against the recess 36 in the back of the top member 15. Any other suitable means of attaching the sleeve 33 to the top member 15, as screws or rivets, will suffice equally as well.

The means for supporting the unit 14 in place is illustrated in Figs. 5 and 6. In Fig. 6 I have shown bracket members 37 having open foot portions through which bolts may pass to fasten the said brackets to the front of the range 10, as shown at Fig. 1. These brackets are reversible. On the top of these brackets I have positioned a horizontal slotted bar member 38 which may be bolted to the free legs of the brackets 37. With such an arrangement it will readily be seen that I may vary the elevation of the bar 38 together with the brackets 37 and at the same time I may vary the position of the bar 38 outwardly or inwardly with respect to the front of the range 10. At Fig. 5 I have shown a perspective view of another bracket 39, the rear end of which is provided with a right-angled wedge member 40 which is adapted to fit in the slot 42 in the bar 38. On the front end of the member 39 I have provided a vertical side member 43, the lower portion of which is slightly curved. The top portion of the member 43 is adapted to be inserted in the recessed portion 36 of the top member 15 between the sleeve 33 and the back of the flange 17, better shown at Figs. 3 and 4. The bottom portion of the member 43 bears against the lower portion of the sleeve 33 and supports it together with the top 15, as shown in Fig. 1. In the position shown in Fig. 1, the sleeve 33 is positioned closely around the conventional perforated sleeve 11, the top edge of which is slightly higher than the bottom edge of the sleeve 33.

It will thus be seen that in an installation of the type shown in Fig. 1, my improved apparatus may be positioned and adjusted in any desired relation to the range burner within reasonable limits. In other words, it may be easily and quickly adjusted to its proper location with a minimum of effort and trouble.

In installations in which the oil burner is built into the range and properly adjusted at the factory, the sleeve 33 and the conventional sleeve 11 may be made in one piece, as in Fig. 8. In such construction the upper portion 33a is open in the same manner as shown in Figs. 1 and 3 in the drawing, the open side being above the upper perforated portion of the sleeve 11a adjacent the oven side of the range. With such construction the brackets and bar member shown in Figs. 5 and 6 will be eliminated but the damper and apparatus shown in Figs. 2 and 7 will be used.

In operation, the damper 21 performs a very essential and important function. When the damper is positioned as shown at Figs. 1 and 2 in the drawing the maximum heat is directed out over the top of the oven 34 passing under the

open end 18 of the top member 15 in much the same manner as disclosed in my previously referred to application. If it is desired to divert heat from the oven to the top of the range the damper 21 may be turned from the outside of the range and tilted to any angle desired thereby allowing the heat to be directly applied to the top of the range. The maximum position is naturally when the damper is in a vertical direction. Inasmuch as practically all range oil burners 10 are installed in pairs it will be apparent that with my dampers 21 set at opposite angles I am able to concentrate or direct the heat in a converging manner to the center of the top of the range thereby greatly intensifying the 15 temperature at this point. At the same time, I may divert only a portion of the heat generated sending some of it to the oven and some to the top of the range, as desired. With such an arrangement the necessity of removing the covers 20 shown in my prior application is avoided and much greater flexibility of heat control is had making it possible to obtain concentrated heat on top of the range and at the same time getting sufficient heat delivered to the oven for baking. 25

Another important feature of the top member 15 which should not be overlooked is the fact that the opening 16 in the top is smaller than the outer sleeve 11 and the result obtained is that the heat is slightly retarded due to the fact that 30 it is slightly converged toward the center of the burner and thereby slowed up to the effect that the base 12 becomes hotter and the gases are more completely burned greatly increasing the efficiency of the burner, the net result of which 35 is more heat with less oil consumption than is possible where the sleeve 11 is not in combination with the unit 14. The heat trapped temporarily under the flanged top member 15 reflects against the base or bowl of the burner causing more perfect combustion of the gases generated thereon. 40

When the above apparatus is used in certain types of older coal ranges where the under side of the top of the range is lower it may be desirable to remove the dampers from the top 15 when 45 all the heat is desired to be directed or diverted under the top of the range owing to the fact that insufficient clearance is present to allow the damper to be turned to a full open position. For such installations I have provided the eye member 32 so that a hook may be inserted therein and the damper 21 removed entirely. When such removal is made it is only necessary to pull out the member illustrated at Fig. 7 and lift the damper 21 off of the top 15 replacing it when it 50 is desired to use the oven. Even under such installations the damper may be rotated part way open and when two units are opposed or converged toward each other sufficient heat will be present on the top of the range for the greater 55 portion of the time.

It will thus be seen that while I have shown my improved apparatus somewhat in detail yet it is to be understood that I may vary the construction in proportion within wide limits without departing from the spirit of the invention. 60

Having thus described my invention what I claim as new is:

1. An improved directional heat control apparatus for range oil burners and the like comprising 70 in combination, an outer sleeve adapted to engage with the base of said burner, the lower portion of said sleeve being perforated in the conventional manner and having an upper portion partially cut away on one side the top edge 75

being semi-circular in outline, a cover adapted to engage over the said semi-circular edge of said sleeve, said cover member having right-angular sides extending around the outside of the upper portion of said sleeve adjacent said semi-circular edge, a projection located on one side of said cover extending out over and beyond the cut away portion of said sleeve, an opening located in the central portion of said cover concentric with said lower portion of the said sleeve, a rotatable damper located in said opening and being trunnioned on said cover, a control lever resiliently connected with said damper the free end of said lever being located outside of said range.

2. An improved directional heat control apparatus for range oil burners and the like comprising in combination, an outer sleeve adapted to engage with the base of said burner, the lower portion of said sleeve being perforated in the conventional manner, an upper sleeve of substantially semi-circular shape concentrically surrounding a portion of the periphery of the upper portion of said conventional sleeve, a cover adapted to engage over the upper edge of said upper sleeve, said cover member having flanged sides surrounding the upper edge of said upper sleeve, a projection located on one side of said cover and extending out over and beyond the open side of said upper sleeve, an opening located in the central portion of the said cover, a rotatable damper located in said opening and being trunnioned on said cover, a control lever resiliently connected with said damper the free end being adapted to extend to the outside of said range for the purpose of regulating said damper, adjustable brackets and bar member attached to the inside front portion of said range said bar being slotted, a hanger member having a wedged shaped portion adapted to engage in said slot of said bar member, upper and lower vertical ends attached to one end of said hanger, the upper vertical end being adapted to engage between the said cover flange and the adjacent side of said upper sleeve, the lower end being adapted to engage against the side of the lower portion of said upper sleeve.

3. In an improved directional heat control apparatus for range oil burners of the class described, a rotatable damper located in the cover

portion of said apparatus for the purpose of regulating and directing the heat flow from said burner, the pivot axis of said damper being located in a horizontal plane.

4. In an improved directional heat control apparatus for use in combination with oil range burners, a heat control attachment of the class described having a top cover with a central opening separating open bearings, a rotatable damper trunnioned on said bearings and adapted to rotate in said opening.

5. In an oil range, a heat and flame director top member adapted to extend above the conventional sleeve of the burner of said range, said top member having a rotatable damper located therein, a resilient and spring retained remote control lever extending through the front of said range and being adapted to engage said damper and operate same from the outside of said range.

6. In an oil range equipped with a conventional oil burner provided with a conventional sleeve, in combination with said range and oil burner, an extension sleeve mounted above said conventional sleeve, said extension sleeve having a top flame and heat deflector head, a rotatable damper located in said head, a remote control connecting said damper and extending through the front of said range, said remote control member being maintained in contact with said damper in a resilient manner, brackets having slotted legs mounted on the inside of the front of said range, a slotted bar adjustably mounted on said brackets, a saddle member having a right-angled wedge end adapted to engage in said slotted bar, the opposite end of said saddle having an upstanding end adapted to engage under the rear side of said top member and a lower end adapted to engage against the side of said extension sleeve.

7. In combination in a combination oil range, an oil burner sleeve perforated on its lower portion and having a portion of one side at the top open, a top member located on the top of said sleeve, a rotatable damper rotatably journalled in said top member, a removable damper control shaft connecting said damper and extending through the front of said range for the purpose of providing a remote control to said damper.

GUY C. CARPENTER.
